UNITED STATES PATENT OFFICE

RICHARD GIBBS, OF PHOENIX, ARIZONA

AIR OR GAS COMPRESSOR

Application filed November 27, 1929. Serial No. 410,049.

This invention relates to a compressor for compressing air or gas whereby the air or gas may be placed in a state capable of being utilized for any purpose.

5 The primary object of this invention is to provide a compressor of the character above mentioned, embodying a rotatably mounted barrel or cylinder containing fluid, such as water or the like, and into which fluid containing barrel or cylinder air is inducted as may be desired to be there compressed and from whence the air so compressed is discharged to be used for any purpose for which it may be desired.

15 Other objects and advantages of the invention will become apparent during a study of the following description, taken in connection with the accompanying drawings, wherein:

Figure 1 is an end elevation of a compressor embodying the features of this invention,

20 Figure 2 is a detail view partly in section and partly in elevation,

Figure 3 is a detail sectional view taken substantially on the line 3—3 of Figure 2 and 25 looking in the direction of the arrows,

Figure 4 is a similar view taken on line 4—4 of Figure 2 and looking in the direction of the arrows,

Figure 5 is a detail sectional view taken 30 substantially on the line 5—5 of Figure 2 and looking in the direction of the arrows,

With reference more in detail to the drawings, it will be seen that the invention comprehends the provision of a suitable base 5 from which rise adjacent opposite ends thereof bearing standards 6 and 7, which standards at their upper ends have formed therewith suitable bearing structures 8 and 7' respectively.

40 These standards and bearings formed thereon provide a supporting structure in a manner to be hereinafter more fully set forth for a compressor unit designated generally by the reference character C.

45 The compressor unit C comprises a cylindrical drum or barrel designated generally by the reference character 9. The barrel 9 comprises complementary sections of cylindrical construction, each of which sections comprise 50 a rear wall 10 and a peripheral wall 11.

The sections of the barrel or drum at their meeting ends are suitably secured together as designated generally at 12. For the sake of convenience, the sections will be designated by the reference characters A and B respectively.

55 Inferiorly, the section A on the inner face of its end wall 10 is provided with a plurality of radially disposed circumferentially spaced impeller vanes 13, which vanes 13 are preferably of the construction shown to advantage in Figure 4 being relatively wide transversely and of somewhat arcuate configuration, said vanes 13 extending inwardly from the peripheral edge of said end wall to terminate short 60 of the center point of said wall.

65 The said impeller vanes 13 cooperate to form therebetween fluid passages 13'. Arranged within the cylinder or drum 9 is an element designated generally by the reference character F, which element F comprises a tubular body portion centrally located within the cylinder, said tubular body portion 14 being opened at its opposite ends and having said ends arranged within the respective sections of the cylinder.

70 At its open ends, the tubular body 14 is provided with annular flanges 15—15, which flanges have their peripheral edges terminating in spaced relation to the peripheral 75 walls of the respective sections A and B.

75 Mounted between the flanges 15—15 adjacent their outer edges, and arranged therebetween in circumferential spaced relation is a plurality of vanes or wings 16, which wings 16 may have their opposite ends welded or otherwise secured to said flanges, and as shown to advantage in Figure 2, these wings 16 extend beyond the adjacent edges of said flanges.

80 At their outer edges, for substantially half the length thereof said wings 16 may be welded to the inner face of the peripheral wall 11 of the section A.

85 The purpose of these wings 16 will be hereinafter made manifest.

80 Formed integrally with the end wall of the cylinder section B is a pintle or stub shaft 17, said stub shaft 17 being rotatably supported in the bearing 8 on the upper end of 100

the standard 6. A shaft 18 has its intermediate portion journaled in the bearing 7' on the standard 7, and at its inner end said shaft 18 is provided with an annular flange 19, which flange 19 in turn at its peripheral edge is provided with an outstanding peripheral flange 20, the outer face or edge of which flange 20 is positioned against the outer face of the end wall 10 of the cylinder section A, and bolts or other fastening elements 21 are threaded through said flange and end wall whereby said shaft 18 is secured to said section A with the flange 19 in spaced relation to said end wall and forming therewith a passage 22.

Thus it will be seen, through the medium of the shafts 18 and 17 the compressor unit is rotatably mounted.

The shaft 17 is provided with a longitudinally extending bore 23 and a relatively long air intake tube 24 extends through the bore and has its inner end extending into the cylinder B for disposition within the tubular body 14 of the element F.

The inner portion of the air intake tube 24 arranged within the tubular body 14 is provided with a plurality of diametrically opposed outlet openings 25. At its outer end, the shaft 18 is provided with a suitable packing flange structure 26.

The outer end of the tube 24 is engaged by a suitable clamp 27 formed on the upper end of a standard 28, which standard 28 at its lower end is bolted or otherwise secured as at 29 to a suitable base or block 30 formed on the base 5. This clamp member 27 is adapted to retain the air inlet tube 24 against rotation.

Interiorly of the cylinder C, and fixedly mounted on the inner end of the air inlet tube 24 is a stationary member comprising an elongated tubular body portion 31 telescopically received within the tubular body 14 of element F and arranged concentrically with respect to the inner end of the tube 24.

At one end, the tubular body 31 terminates in a somewhat disk like head 32 arranged between the opposed faces of the end walls 10 of the section B and the adjacent flange 15 as shown to advantage in Figure 2.

The said head 32 is provided with a plurality of longitudinally curved radial water ducts 33 communicating at their inner ends with the tubular body 31 and at their opposite ends communicating with the interior of the cylinder.

At the inner end of the water duct 33 said head 32 is provided with a hub 34 welded or otherwise secured to the air inlet tube 24. In actual practice, the shaft 18 is connected on its outer end with any suitable driving means designated generally by the reference character 34 whereby rotary motion from any suitable source of power may be imparted to said shaft 18 and then to the cylinder 9.

Said cylinder 9 will contain a certain amount of water or other fluid and air from any suitable source will be inducted through the inlet tube 24 to discharge therefrom through the opening 25 into the tubular body 31 to flow therefrom in the direction indicated by the arrows in Figure 2.

During the rotation of the cylinder the fluid therein will distribute itself around the cylinder evenly due to centrifugal force. Some of the fluid will pass through the ducts 33 and thence through the tubular body 31, which tubular body 31 forms a mixing chamber designated by the reference character 35.

As the fluid passing through said mixing chamber 35 flows past or over the openings 25 of the air intake pipe 24, this fluid will pick up air in the form of fine bubbles and the mixture then passes into the passages or ducts 14, which ducts due to the rotation of the cylinder 9 may be designated as the rotating ducts, and from said ducts 14 will pass between adjacent impeller wings 16 into the space between the flanges 15-15, which space between said wings may be designated the separating chamber, and from this separating chamber, it is apparent that air being lighter than the water will separate from the water and go into the space between the flanges 15-15 which space may be designated an air chamber and is denoted by the reference character 36.

The fluid or water being heavier, centrifugal force holds the fluid outside. The water now being free of air will pass between the wings 16 and between the peripheral edge of the flange 15 and the peripheral wall of the cylinder section B into the ducts 33 in the head 32 to repeat the cycle.

The air accumulated in the air chamber 36 will pass therefrom through air ducts 37 into the passages 22, there being two of such ducts 37 extending through diametrically opposed vanes 13 and leading from said air chamber 36 into the said passage 22 as shown to advantage in Figures 2 and 4.

From the passage 22 air then passes into what may be termed an air collecting chamber designated generally by the reference character 38. This collecting chamber 38 is formed by an annular member 39 mounted on the shaft 18, which annular member 39 on its inner periphery is provided with an annular groove or channel 40 communicating through the medium of ducts 41 formed in the said shaft 18 with a passage or bore 42 extending longitudinally through said shaft for a short distance, said bore or passage 42 at its open end communicating with the passage 22 as shown to advantage in Figure 2.

Mounted on the shaft 18 on opposite sides of the annular member 39 are suitable gland nuts 43 having threaded engagement at 44 with the said annular member 39 and between which annular member 39 said gland nuts are

interposed in suitable compressed packings 45.

This collector structure is non-rotatable on said shaft, and leading downwardly from the collector is a conduit pipe 46, the upper end of which pipe has threaded engagement with the annular member 39 to communicate with the channel or groove 40 formed therein.

This conduit 46 leads to any place remote from the compressor for conveying the air from the compressor to be used for any purpose for which it may be desired.

The said collector is held against rotation through the medium of a suitable clamping bracket 47 projecting laterally from the lower portion of the post 7 and engaging with the conduit 46 as shown to advantage in Figure 2.

It is to be noted, that the impeller vanes 13 cooperating with the inner wall of the cylinder section A forms an impeller which is of greater diameter than the stationary head 32 so that with the result that the impeller that rotates the mixture of fluid and air be greater than that part of the compressor that stops the rotation in the medium through which is created a pressure on the air or gas.

It will also be appreciated, that with a compressor of this character, should the demand of air lessen or stop while rotation is continued there will be no very large rise in pressure of the air because the air will pass over that flange 15 adjacent the head 32 together with the fluid, it being recalled that during the operation of the device the air going into the air chamber 36 leaves the water so free of the air to pass over said flange 15.

However, upon the condition just mentioned and as stated the air and fluid will both pass over the said flange 15. Under these conditions, as the mixture of air and fluid gets to the mixing chamber, there will be no more air taken in as the fluid is already a saturated solution of air and water.

Hence the work of compression is distinctly related to the demand for air and power requirements also are proportional to the demand for air.

Should it be desired to use the compressor on high pressure, it will be necessary to dissipate some of the heat generated. This dissipation of the heat can be obtained by ribbing the surface of the working barrel on the outside and thus increase the radiation space.

It is believed that from the foregoing description, taken in connection with the accompanying drawings a clear understanding of the operation, construction, utility and advantages of a structure of this character will be had by those skilled in this art without a more detailed description thereof.

Having thus described my invention, what I claim as new is:

1. In a compressor of the class described, a base, bearing brackets rising from said base,

a rotatably mounted cylinder, shafts extending from the opposite ends of said cylinder, said shafts having their outer ends journaled in said bearing brackets, radially disposed impeller vanes formed on the inner face of one end wall of said cylinder, said vanes being circumferentially spaced to provide passages therebetween, a tubular element arranged within said cylinder, said tubular element open at its opposite ends, flanges formed on said tubular element at said ends, impeller wings arranged in circumferentially spaced relation between said flanges at the outer ends of said flanges, said wings at their outer edges being secured to an adjacent portion of the peripheral wall of said cylinder, said cylinder being adapted to receive fluid, one of said shafts having a longitudinally extending bore therethrough, an air inlet tube arranged in said bore and having one end thereof extending into said tubular member, said one end of said tube being provided with a plurality of diametrically opposed outlet openings, and a fluid within said cylinder during the rotation of said cylinder adapted to intermingle with the air discharged through said outlet opening, the space between said flanges forming an air chamber for receiving the air separated from said fluid during the rotation of said cylinder, said passages and said wings providing unobstructed communication between said tubular member and said air chamber, a compressed air collector, and passages leading from said air chamber to said collector.

2. In a compressor of the class described, a base, bearing brackets rising from said base, a rotatably mounted cylinder, shafts extending from the opposite ends of said cylinder, said shafts having their outer ends journaled in said bearing brackets, radially disposed impeller vanes formed on the inner face of one end wall of said cylinder, said vanes being circumferentially spaced to provide passages therebetween, a tubular element arranged within said cylinder, said tubular element open at its opposite end, flanges formed on said tubular element at said end, impeller wings arranged in circumferential spaced relation between said flanges at the outer ends of said flanges, said wings at their outer edges being secured to an adjacent portion of the peripheral wall of said cylinder, said cylinder being adapted to receive fluid, one of said shafts having a longitudinally extending bore therethrough, an air inlet tube arranged in said bore and having one end thereof extending into said tubular member, said one end of said tube being provided with a plurality of diametrically opposed outlet openings, and a fluid within said cylinder during the rotation of said cylinder adapted to intermingle with the air discharged through said outlet opening, the space between said flanges forming an air chamber for receiving the air

separated from said fluid during the rotation of said cylinder, said passages and said wings providing unobstructed communication between said tubular member and said air chamber, a compressed air collector, and passages leading from said air chamber to said collector, means for retaining said air in said tube against rotation, and a member mounted on said one end of said tube, said member including a head having a plurality of passages formed therein communicating with the interior of said cylinder whereby the fluid within said cylinder may be conducted across said air outlet opening during the rotation of said cylinder.

3. In a compressor of the character described, a fluid retaining cylinder, means for rotatably supporting said cylinder, a mixing chamber arranged within said cylinder concentrically of said cylinder, an air inlet tube extending into said cylinder and terminating within said mixing chamber, means for retaining said tube against rotation, a stationary member mounted on the inner end of said air inlet tube, said stationary member including a plurality of passages communicating with the interior of said cylinder for conducting the fluid in said cylinder into said mixing chamber, said air inlet tube having a plurality of outlet openings formed therein to provide communication between said inlet tube and said mixing chamber, means within said cylinder for agitating the mixture within said cylinder, means for separating the air from said fluid, a collector for receiving the air thus separated, and a discharging conduit from said collector.

4. In a compressor of the character described, a fluid retaining cylinder, means for rotatably supporting said cylinder, a mixing chamber arranged within said cylinder concentrically of said cylinder, an air inlet tube extending into said cylinder and terminating within said mixing chamber, means for retaining said tube against rotation, a stationary member mounted on the inner end of said air inlet tube, said stationary member including a plurality of passages communicating with the interior of said cylinder for conducting the fluid in said cylinder into said mixing chamber, said air inlet tube having a plurality of outlet openings formed therein to provide communication between said inlet tube and said mixing chamber, means within said cylinder for agitating the mixture within said cylinder, means for separating the air from said fluid, a collector for receiving the air thus separated, and a discharging conduit from said collector, said agitating means comprising a plurality of propeller vanes arranged within said cylinder at one end of said mixing chamber.

5. In a compressor of the class described, a fluid containing cylinder, means for rotating said cylinder, a tubular member open at

its opposite end and arranged within said cylinder concentrically of said cylinder, a plurality of circumferentially spaced impeller vanes extending inwardly from the peripheral wall of said cylinder at one end of said tubular member, a plurality of circumferentially spaced wings carried by said tubular member, said wings having their outer edges secured to the peripheral wall of said cylinder whereby said tubular member is anchored within said cylinder for rotation therewith, said tubular member at its opposite end provided with outstanding flanges, said wings having their inner edge portions arranged between the outer edges of said flanges in spaced relation to said tubes, an air inlet tube extending into said cylinder and terminating within said tubular member, means for retaining said air inlet tube in a stationary position, and passages in said cylinder for conveying fluid in said cylinder across the opening formed in the inner end of said air inlet tube, an air collector arranged exteriorly of said cylinder, and an air conduit leading to said air collector.

6. In a compressor of the class described, a rotatable fluid containing cylinder, means for rotatably supporting said cylinder, a non-rotatable air inlet tube extending into said cylinder, a tubular member arranged concentrically on said air inlet tube within said cylinder, said tubular member at one end terminating in an enlarged head, radial passages in said head communicating with the interior of said tubular member whereby fluid within said cylinder may be conducted through said tubular member during the rotation of said cylinder, whereby said fluid is mixed with the air discharged from the inlet tube, impeller vanes arranged within said cylinder at that end of the tubular member remote from said head, circumferentially spaced inwardly extending wings mounted on the peripheral wall of said cylinder, said wings disposed at right angles to said vanes, said wings and said vanes forming passages from one end of said tubular member to the passages formed in said head, an air collecting chamber formed in said cylinder for receiving the air separated from said fluid by centrifugal force, and an outlet for the air in said air chamber leading from said air chamber to the exterior of said cylinder.

7. In a compressor of the class described, a rotatable fluid containing cylinder, means for rotatably supporting said cylinder, a non-rotatable air inlet tube extending into said cylinder, a tubular member arranged concentrically on said air inlet tube within said cylinder, said tubular member at one end terminating in an enlarged head, radial passages in said head communicating with the interior of said tubular member whereby fluid within said cylinder may be conducted through said tubular member during the rotation of said

cylinder, whereby said fluid is mixed with the air discharged from the inlet tube, impeller vanes arranged within said cylinder at that end of the tubular member remote from said head, circumferentially spaced inwardly extending wings mounted on the peripheral wall of said cylinder, said wings disposed at right angles to said vanes, said wings and said vanes forming passages from one end of said tubular member to the passages formed in said head, an air collecting chamber formed in said cylinder for receiving the air separated from said fluid by centrifugal force, an outlet for the air in said air chamber leading from said gas chamber to the exterior of said cylinder, a compressed air collector exteriorly of said cylinder at one end of said cylinder, and said air outlet leading to said collector.

10 ing relatively longer than the first referred to passages, and a plurality of circumferentially spaced longitudinally extending wings extending inwardly from the peripheral wall of the container and forming therebetween 70

15 passages communicating the first and second mentioned series of passages, a member carried by said container for rotation therewith, said member having an air passage therein, a passage leading from the container to said 75

20 member for conducting the compressed air from the container to said member, and a second member concentrically arranged about said first mentioned member, said second member being non-rotatable and communicating with the passage in said first mentioned member, and a conduit leading from 80

25 said second mentioned member.

8. In a compressor of the class described, 85 a rotatable fluid containing cylinder, means for rotatably supporting said cylinder, a non-rotatable air inlet tube extending into said cylinder, a tubular member arranged concentrically on said air inlet tube within said cylinder, said tubular member at one end terminating in an enlarged head, radial passages in said head communicating with the interior of said tubular member whereby fluid within said cylinder may be conducted 90 through said tubular member during the rotation of said cylinder, whereby said fluid is mixed with the air discharged from the inlet tube, impeller vanes arranged within said cylinder at that end of the tubular member remote from said head, circumferentially spaced inwardly extending wings mounted on the peripheral wall of said cylinder, said wings disposed at right angles to said vanes, said wings and said vanes forming 95 passages from one end of said tubular member to the passages formed in said head, an air collecting chamber formed in said cylinder for receiving the air separated from said fluid by centrifugal force, an outlet for the air in said air chamber leading from said 100 gas chamber to the exterior of said cylinder, a compressed air collector exteriorly of said cylinder at one end of said cylinder, and said air outlet leading to said collector, said collector being non-rotatable.

9. In an air compressor, a rotatable container, means for supporting the same, said container adapted to contain fluid, an axial chamber in the container, relatively short radial fluid passages communicating at one end with said mixing chamber, and at their opposite ends with the interior of said container whereby the fluid in the container during rotation of the same is conducted to the mixing 105 chamber, means for forcing air into said mixing chamber, radial passages at the other end of said mixing chamber through which the air and fluid from the mixing chamber is conducted toward the peripheral wall of said container, said last mentioned passages be- 110
